UNITED STATES PATENT OFFICE.

LOUIS B. MARKS, OF CHICAGO, ILLINOIS.

DESIGN FOR A DISPLAY-CARD.

SPECIFICATION forming part of Design No. 35,055, dated September 10, 1901.

Application filed August 16, 1901. Serial No. 72,275. Term of patent 3½ years.

To all whom it may concern:

Be it known that I, LOUIS B. MARKS, a citizen of the United States, residing at Chicago, in the county of Cook and State of Illinois, have invented and produced a new and original Design for Display-Cards, of which the following is a specification, reference being had to the drawings forming a part thereof.

In the accompanying drawings, Figure 1 is a face view of a display-card embodying my design. Fig. 2 is an edge view of the same.

As shown in the drawings, the leading or material features of my design lie in the combination and arrangement of objects upon the mat or background of a display-card. Cards of this character are intended for decorative purposes, the objects chosen for mounting upon the card being such as may be presumed to accord with the tastes and habits of the person in whose room the card is hung.

A is the mat or base, oblong in form, adapted to be suspended by one of its ends by means of the loop B, formed of a shoe-lace. Upon the upper portion of the face of the base are secured a number of playing-cards C, and upon the lower portion of the base I attach the empty mug D, adapted to receive matches. Arranged upon the card between the playing-cards C and the mug D are a cigar-stump E, a half-consumed cigarette F, a match G, and several poker-chips H, while to one of the lower corners of the card is affixed a piece of sandpaper I.

I claim as my invention—

The design for a display-card, substantially as herein shown and described.

LOUIS B. MARKS.
